UNITED STATES PATENT OFFICE.

JOSEPH EARL LEONARD, OF CEDAR RAPIDS, IOWA.

STOVE-KEY-PLATE RATCHET-SUPPORT.

1,095,333.

Specification of Letters Patent.

Patented May 5, 1914.

Application filed November 8, 1912. Serial No. 730,166.

To all whom it may concern:

Be it known that I, JOSEPH EARL LEONARD, a citizen of the United States, and a resident of Cedar Rapids, in the county of Linn and State of Iowa, have invented certain new and useful Improvements in Stove-Key-Plate Ratchet-Supports, of which the following is a specification.

My invention is an improvement in stove top plate ratchet supports, and has for its object a device of the character specified, designed to overcome the objections to the ordinary support of this character, and wherein means is provided for supporting the plate in a variety of adjustments, automatically operating by the movement of the plate.

In the drawings: Figure 1 is a plan view of a portion of a stove provided with the improved support; Fig. 2 is a perspective view of the support detached; Fig. 3 is a side view partly in section; Fig. 4 is a front view of the ratchet bar; and Fig. 5 is a view similar to Fig. 3, showing the plate lifted.

The present embodiment of the invention comprises a substantially triangular plate 1, having a plurality of openings 2, three in the present instance, through which may be passed screw bolts 4 for securing the support to the top plate 5.

The plate 1 is provided with an angular arm 6 extending from the apex thereof, parallel with one side, and offset laterally from the said side. The said arm is approximately cross shape in section, and near its end the arm is cut away at each side to form a head 7 connected to the arm by a reduced portion 8. A bearing lug 9 having a transverse perforation is secured to the casing 11 of the stove, by means of screw bolts 12 passing through a base plate 13 integral with the bearing lug, and a ratchet bar 14 is pivoted to the lug. The ratchet bar is provided at its upper end with a pair of laterally spaced perforated ears 15, fitting on opposite sides of the bearing lug, and a rivet 16 is passed through the ears and the lug for pivotally connecting the ratchet bar to the bearing lug. The ratchet bar is longitudinally slotted, as shown at 17, and the slot is enlarged laterally at each end, as shown at 18 and 19 respectively. The enlargements 18 and 19 are for the purpose of permitting the passage of the head 7 of the arm 6, and the reduced portion 8 of the said arm is capable of moving in the slot 17. On the opposite

side from the support, the ratchet bar is provided with a series of notches 20, three in the present instance, for engagement by the head 7, as shown in Fig. 3, and the notches are shaped to fit the head, as clearly shown in the said figure.

In operation, the ratchet bar depends vertically from the bearing lug, and the arm 6 is so arranged with respect to the plate 1, that when the top plate is in normal position, the head 7 of the arm will be in position to engage and pass through the opening 18 of the ratchet bar. The top plate is lifted by the usual lid lifter, not shown, engaging the usual lifter hole 21, and it will be evident that when the plate is lifted, the arm 6 will swing downwardly and the head 7 will come into position to engage one of the notches 20 of the ratchet bar. When the arm 6 is in the position designated by II, the ratchet bar will support the plate in this position, and in like manner the plate will be supported in the position III. When, however, the arm is in the position designated IV, the ratchet bar will disengage from the arm, since the head 7 is at the enlargement 19. When the top plate is dropped back into normal position designated I, the arm 6 will push the ratchet bar into the dotted line position designated V and the head 7 will pass through the enlargement 18, permitting the ratchet bar to drop into the full line position of Fig. 3.

I claim:

1. The combination with the stove and the movable top plate, of a ratchet bar having a longitudinal slot pivoted to the frame of the stove and depending therefrom, said slot being enlarged laterally at each end, and the said bar having ratchet teeth on its rear face, said teeth facing the lower end of the bar, an arm having means at one end whereby it may be secured to the said top plate and extending toward the ratchet bar, said arm being reduced laterally near its outer end to form a head connected to the arm by a reduced portion, said head being adapted to pass through the enlargements at the ends of the slot and to engage the ratchet teeth, the reduced portion of the arm moving in the slot.

2. The combination with the stove and the movable top plate, of a ratchet bar having a longitudinal slot pivoted to the frame of the stove and depending therefrom, said slot being enlarged laterally at each end, and

the said bar having ratchet teeth on its rear face, said teeth facing the lower end of the bar, an arm secured at one end to the said top plate and extending toward the ratchet bar, said arm being reduced laterally near its outer end to form a head connected to the arm by a laterally reduced portion, said head being adapted to pass through the enlargements at the ends of the slot and to engage the ratchet teeth.

3. The combination with the stove top and the movable top plate, of a ratchet bar pivoted to the stove top and depending

therefrom, an arm rigid with the movable top plate and having at its free end a cross head, the ratchet bar having a longitudinally extending slot provided at each end with an enlargement for permitting the passage of the head and having stops on the opposite face from the movable top plate for engagement by the cross head to support the top plate in adjusted position.

JOSEPH EARL LEONARD.
